Inventor

Charles A. Widmer

By his Attorney

Brett Schuer

UNITED STATES PATENT OFFICE.

CHARLES A. WIDMER, OF PATERSON, NEW JERSEY.

DRILL PRESS.

1,424,538.

Specification of Letters Patent. Patented Aug. 1, 1922.

Application filed November 13, 1918. Serial No. 262,265.

To all whom it may concern:

Be it known that I, CHARLES A. WIDMER, a citizen of the United States, and a resident of Paterson, in the county of Passaic 5 and State of New Jersey, have invented certain new and useful Improvements in Drill Presses, of which the following is a specification.

Drill presses in which the drill spindle is power-driven to perform its thrust-movements are of three known types, to wit; those in which the drill-spindle is power-reciprocated constantly, in which the drill-spindle is brought down to a certain point 10 manually and then manually thrown into connection with the power drive mechanism, and finally those in which the drill-spindle is depressed manually until it contacts with the work, whereby the resulting resistance 15 causes the drill-spindle to be coupled with the power-drive mechanism for continuing the downward thrust. The third known type is an improvement on the first and second in that on the one hand the movements 20 of the drill-spindle are subject to manual control and on the other require only one of the attendant's hands to be occupied. My present invention represents a further advance in the art, notably in this, that 25 whereas, as in the third type, the movements of the drill-spindle are subject to manual control and such control involves the occupation of only one of the operator's hands, the coupling of the drill-spindle with the 30 power drive mechanism is dependant not on contact of the tool with the work but on the drill-spindle first moving a definite distance under manual influence. Thus, in a practical application of my invention, since the 35 coupling occurs entirely without reference to contact of the tool with the work and the utilization of incidental resistance to effect it, it may very desirably be adapted to occur just before the contact accrues, 40 whereby the tool comes to the work subject to a constant, power drive effort, and the operator is saved the fatigue incident to overcoming resistance in order to effect the coupling, less skill, moreover, being required on the operator's part, and certain 45 other advantages resulting and which will be evident to those skilled in the art.

In the accompanying drawings,

Fig. 1 is a front elevation of a drill-press embodying my improvements.

55

Fig. 2 is a fragmentary plan, partly in section.

Fig. 3 is a fragmentary elevation.

Fig. 4 is a detail sectional view.

Fig. 5 is a fragmentary view illustrating 60 the locking pawl and release mechanism.

Similar characters of reference designate corresponding parts throughout the several views.

The drill-press, in connection with which 65 the invention is herein illustrated, may be of any well-known or special design, 10 designating the pillar and 11 and 12 the spaced horizontal head members of the frame of the machine, 13 the forward pulley of a 70 belt-and-pulley driving means arranged in said head members, 14 the drill-spindle splined in the sleeve 15 which affords the journal part of said pulley, 16 the sleeve through which the spindle downwardly projects, being rotative therein but confined 75 against vertical movement relatively thereto by the collars 17 and 17' thereon, 18 the frame arm, adjustable up and down on the pillar, in which sleeve 16 is splined, 19 the 80 work table, 20 the chuck for the tool suitably attached to the lower end of the spindle—the sleeve, spindle and chuck forming an 85 up-and-down movable tool-carrier—and 21 a rotary horizontal shaft journaled in the frame-arm 18 and having a pinion 22 (Fig. 4) meshing with rack teeth 23 on the sleeve and a fixed head 24 provided with radial handles 25, the parts 21 and 25 forming 90 means for manually moving the carrier up and down. To hold the carrier normally elevated, I may provide any suitable and well-known means (not shown).

In the adaptation herein shown, the construction is such that the carrier, normally 95 held elevated, is adapted to be started on its downward course manually, by turning shaft 21 in the proper direction by means of its described handles and, when it has thus been made to proceed downward a definite distance, to be driven downward by power a definite further distance, thereupon to be released and so return to the elevated position under the influence of the means normally 100 acting to hold it in that position. To this 105 end, there are a going driving means and a

power transmitting coupling to connect the carrier with the driving means and which will now be described.

A rotary vertical shaft 26 is suitably mounted parallel to the drill-spindle 14, being driven from the pulleys 27 thereof through belt 28 and pulleys 29 of said shaft. Through intermediate mechanism this rotation of shaft 26 is communicated to a further shaft 30 designed to have an actual vertical motion relatively to said shaft 26 and being stepped on an anti-friction bearing 31 as well as having affixed to it a worm 32 and a collar 33, Fig. 3, the step bearing, worm and collar fitting between opposed abutments 34, Fig. 3, in the casing and so confining the shaft against vertical movement relatively to the casing.

Shaft 21 has a reduced extension 35 on which is freely revolute a gear member 36 which comprises peripheral worm teeth 37 and peripheral gear teeth 38 (the teeth 37 and 38 being formed in the illustrated construction as two separate parts keyed together at 39). Keyed on the shaft is the hub 40 of a face plate 41 to which there is affixed, spaced therefrom by disks 42 and concentric with the shaft, an annular plate or ring 43; the means for securing ring 43 to the face plate may be screws 44. On studs 45, supported at their ends by the ring and face plate, are journaled pinions 46, meshing with the gear teeth 38. 47 designates a gear having a hub 48 journaled between and concentric with the hub 40 of the face plate and the bearing portion 49 of the casing 50, the same comprising an interior peripheral series of gear teeth 51 and an exterior peripheral series of teeth 52, in the form of ratchet teeth. A collar 53, secured in bearing portion 49, prevents displacement of shaft 21 to the right by affording an abutment to the face plate, which is keyed on the shaft, as stated. The interior teeth 51 mesh with the pinions 46, and it will now be obvious that if, assuming the member 36 to be constantly rotated from the work wheel 32 and the member 47 be alternately held against and left free to rotate, shaft 21 will be alternately rotated and non-rotated or idle, respectively; that is, with member 47 held against rotation, the parts 36 and 46 will constitute planetary gearing and so shaft 21 will be driven through the face plate and, with member 47 released, rotation of member 36 will be transmitted to member 47 through the pinions 46 without affecting the face plate. For controlling the member 47, there is pivoted in the casing 50 on a shaft 54 parallel with shaft 21 a two-armed pawl 55, one arm of which has a hook 56 to engage the ratchet teeth 52 of member 47. The shifting of the pawl is effected from the tool carrier in the following manner.

65 A collar 58 is secured to the sleeve 16 and

has suitably held therein a depending rod 59 which slides up and down in a fixed guide 60 of the casing. In a collar 61, suitably affixed to the rod 59, is pivoted a dog 62 whose inner arm is normally held by the weight of its longer outer arm in the horizontal position indicated (Fig. 5), and bears against stop 63 immediately over the protruding arm of lever 55. When the carrier descends, the dog will engage said protruding arm of said lever 55 and shift the position of disengagement of its pawl 56 to one of engagement with the teeth 52 of gear 47; but during the return movement, the dog will be shifted idly on its pivot by 75 said arm, as indicated by dotted lines. On the sleeve 16 there is also arranged a strap or further collar 65 adapted to be adjusted vertically thereon by a clamp screw 66, said strap having a toe 67 on its underface which, 80 a predetermined time after dog 62 shifts the pawl 56 into position for engagement, impinges upon a projection 68 of the arm 69 of a rock shaft 70. This rock shaft carries a double-stepped detent 71 which, in position of engagement of the pawl and teeth shown in Fig. 5, is designed to engage an arm 72 of the pawl lever 55 to lock the position of engagement; and when the shaft 70 is rocked through engagement of toe 67 85 with projection 68, arm 72 slips out of engagement with the upper step of the detent and into the lower position, wherein the pawl 56 through the outward movement of its carrying arm 55 becomes released from engagement with the teeth 52. This release may also be effected manually by directly actuating the projecting arm 69 of rock shaft 70. Pawl 56 is urged outwardly a limited extent through the action 90 of a spring 73 which yieldingly retains the said pawl in its carrying arm 55 and the arm 72 is spring-urged toward the detent 71 through a spring 74. The position of the collar 65 is adjusted to suit the degree of feed desired, and the dog 62 is so positioned that when the drill-spindle descends, the latter will be coupled with the power drive just before said spindle contacts with the work.

The operation will now be obvious to those skilled in the art. The elements 15, 27, 28, 29, 26, 30, 32 and 36 may be regarded as a going driving means, the elements 14, 16, 21 and 41 as a tool carrier—including 110 driven means movable back and forth—and the elements 46 and 47 and pawl 56 as a coupling for operatively connecting the driving and driven means having a moving master member (the pawl) movable to one 115 position to make or establish and to another to break or disestablish the coupling. The carrier is normally held with collar 17' abutting the frame arm 18.

When the carrier is elevated, the master 120

member stands in position of disengagement. On the operator's turning shaft 21 to depress the carrier, the dog 62 at a certain point in the descent of the carrier will trip 5 the master member to lock the gear member 47 against rotation, thus making or establishing the coupling so that the power of the going driving means will be transmitted to and continue downward the carrier. 10 The carrier will continue downward, power driven, to a point (predetermined by adjusting up or down collar 65) where toe 67 impinges and trips back the master member, returning the same to the position 15 to release gear member 47, thus breaking or disestablishing the coupling, and, the carrier now being free, returns to the elevated position, the dog 62 wiping idly past the lever 55. The power applied to the

tool is thus not only of a constant character while the tool is at work, but is cut off at a definite point.

I claim:

In combination, the frame, a tool-carrier including train including a rotary driven 25 member, a rotary driving gear member, a free rotary gear, said members and the gear being concentric, a pinion meshing with the gear and journaled in one and meshing with the other of said members, 30 and a rotation preventing detent device for the gear movable into and out of locking relation thereto and actuatable by a part of said train.

Signed at New York, in the county of 35 New York and State of New York, this seventh day of November, A. D. 1918.

CHARLES A. WIDMER.
